poration of Illinois

Application October 3, 1942, Serial No. 108,414

To all whom it may concern:

Be it known that I, Chauncey E. Waltman, a citizen of the United States and resident of Chicago, in the county of Cook and State of Illinois, have invented a new, original, and ornamental Design for a Table, of which the following is a specification, reference being had to the accompanying drawing, forming a part thereof.

Figure 1 is a view in perspective of the table, showing my new design.

Fig. 2 is a fragmentary sectional view, taken along the line 2—2 of Fig. 1, for the purpose of more clearly illustrating the contour of the article.

The two sides of the table not shown in Figure 1 are substantially the same as the sides of the table shown in said figure.

I claim:

The ornamental design for a table, substantially as shown and described.
